UNITED STATES PATENT OFFICE.

ELMER PEMBERTON, OF HYDE PARK, CALIFORNIA.

HEATING AND VENTILATING CONSTRUCTION.

Application filed November 29, 1920. Serial No. 427,252.

To all whom it may concern:

Be it known that I, ELMER PEMBERTON, a citizen of the United States, residing at Hyde Park, in the county of Los Angeles and State of California, have invented new and useful Improvements in Heating and Ventilating Constructions, of which the following is a specification.

This invention relates to a construction 10 for effecting the ventilating of a room or rooms as well as the heating thereof, and particularly pertains to a ventilating system of the open fire place type in which foul air is removed from a room and replaced by 15 fresh air due to the natural flow of air which flow may be accelerated by a suitable heating means, and which flow may be caused to induce other flows of air from remote points without necessitating the heating of the air 20 coming from the remote point.

An object of this invention is to draw foul air adjacent the floor from the room and thereby create a tendency for fresh air to enter at any desired point about the room 25 or adjoining rooms.

Another object of the invention is to effect the ventilation of a room by the use of an open fire place permitting the direct removal of foul air from remote points within 30 the room or from other remote points without setting up a diversity of objectionable air currents throughout the room, and preventing the commingling of fresh air with the foul air present.

Another object of the invention is the 35 conservation of heat required for producing the ventilating effect.

A further object of the invention is to provide a chimney and open fire place and 40 a series of flues so arranged and communicating with each other as to create a tendency of upward flow of air in the flues, and with the lower portion of the flues arranged to receive air from the lower portion of the 45 room, and to provide means for effecting the efficient removal of foul air from the room and which chimney and open fire place may be used with or without a heating agency in creating a draught therein.

Other objects will appear hereinafter.

The invention is illustrated in the accompanying drawing, in which:

Figure 1 is a view in vertical section partly in front elevation showing the construction of the fire place and flues, as seen 55 on line 1—1 of Figure 3.

Figure 2 is a view in horizontal section as seen on the line 2—2 of Figure 1.

Figure 3 is a view in vertical section as seen on the line 3—3 of Figure 1.

It is well known that the usual open fire place with a heating means therein is adapted to cause a natural flow of air through a room even when no heat is being generated, and is particularly adapted to cause a rapid 65 flow of air when the heat is being generated.

The usual construction, however, results in a definite line of flow of air which flow begins at a point where the fresh air enters the room and proceeds direct to the fire 70 place causing eddies to be caused in the room and further causing much of the foul air to become stratified in the room without being driven out by the advancing fresh air, thereby requiring the heating and displacement of large quantities of foul air and 75 fresh air in order to remove the requisite amount of foul air, and an objectionable draught of cold air is caused to move along the floor.

It is known that when air is heated it expands and becomes lighter in volume, and as it expands a difference in potential is created between the lighter warm air and the heavier cool air bearing upon it resulting in the 80 warm air being set in motion. To move a given amount of air by this method requires the expenditure of a definite amount of heat and it is obvious that when fresh air and foul air are permitted to commingle large 85 volumes of air must be set in motion in order to effect the removing of the foul air, requiring the expenditure of excess quantities of heat. The purpose of this invention is to obtain the benefits accruing from the 90 open fire place, but to eliminate some of the objectionable features thereof by a construction that will effect ventilation with or without heat being generated, which may also be used for efficiently heating a room when heat 95 is desired or in which the generation of heat may be employed to facilitate the removal of air during warm weather without necessitating heating the room.

Referring to the drawing, 5 indicates a 105 space partially enclosed by an arch 6 and the two side walls 7. Gas burners 8 are shown situated within a casing 8' and have their head portions located in enclosures formed by housings 9 covered by an open 110 grate 10. Air passages 11 pass through the side walls 7 and leading therefrom are ducts

12 communicating with the casing 8' and the air passages 11. These air passages are provided with ducts 12 adapted to carry air into the burners to support combustion 5 of the fuel. A port or opening 13 is provided in the arch wall and establishes communication with the smoke flue 14, the smoke flue being adapted to carry off the products of combustion. Baffles 15 are provided in the arch and deflect some of the heated air into the room. An air duct 16 leads from a remote point or branches into other ducts leading from other remote point 10 to the lower portion of the smoke flue 14. The chimney 17 is provided to which the smoke flue leads with two other flues 19 and 20 which open into the chimney at points 15 21 and 22, and these points of juncture with the chimney are so situated in relation to the smoke flue that an upward flow of air in the smoke flue will produce an upward flow of air as well in the flues 19 and 20, these flues 19 and 20 having ducts 23 and 24 opening into their lower end; the duct 23 20 being provided for the purpose of conveying foul air from a remote point or points and delivering it to the flue 20. The duct 24 communicates with the atmosphere and is adapted to carry cool air from the exterior 25 of the room or building into the flue 19 and thereby lower the temperature of the contents of the chimney above the points 21 and 22. This cool air duct may be provided with a regulable means such as a damper 25 to control the amount of air 30 flowing therethrough.

The operation is as follows: When the burners are lighted the heated products of combustion rise and pass through the port 40 and up to the flue, this induces an upward flow of air in the flues 19 and 20 and thus the foul air is drawn through the ducts from the remote points and carried out 45 through the chimney. Some of the heated air rising from the grate is drawn through the air passages 11 through the air ducts 12-12 and caused to pass through the burners by the suction induced by the flow of gas through the burners, thus the burners 50 are always supplied with superheated air resulting in a higher temperature of the products of combustion causing these products of combustion to rise more rapidly. This superheating of the air serves to conserve the heat. The air ducts may be so proportioned that they will transmit to the burners a quantity of warm air only sufficient to support combustion without supplying any extraneous atmospheric air not 55 needed for combustion. This will result in a high temperature of the products of combustion resulting in high velocity through the flue thereby inducing the maximum suction effect on the adjoining flues and air ducts.

By this method it is obvious that the maximum kinetic energy of the rising products of combustion may be used to effect the removal of air through the flues without the necessity of the air being moved having to 70 pass through or in proximity to the burner and thereby wasting useful heat. It is also known that the higher the temperature of air rising from the heating element the greater is the velocity in passing through a 75 flue and the greater the velocity in the flue 19 the greater is the suction effect produced on the adjoining flue.

The amount of air actually required to support combustion with the burners is comparatively small relative to the quantity of air to be moved. The temperature resulting from the combustion of fuel and only such air as is needed for its complete combustion is very high and this value is increased by 80 the fact that the ducts supply this limited portion of air at a temperature above that of the surrounding atmosphere. A high temperature of the fire may be thus maintained permitting a rapid removal of air with a 85 quantity of heat only sufficient to effect the resulting ventilating without the necessity of heating the room; thus the system is particularly suited for drawing cool moist air into a room in warm weather and by the 90 proper distribution of the vent ducts various ventilation and air conditioning effects may be accomplished.

If it is desired to heat the room as well as ventilate it more heat may be generated 100 so that the products of combustion rising from the fire are deflected by the baffles and caused to radiate some of their heat to the air in or adjacent to the fire place before said products pass into the flue; a portion 105 of the air thus warmed flowing out into the room to displace a portion of that which is drawn into the ducts the inlets of which are remote from the fire place.

When such heat is being generated and only small ventilating effect is required the temperature of the gases reaching the chimney 17 will be high. Particularly when the outside air is cold the gases on passing from the top of the chimney become suddenly 110 chilled and cause a damping effect at the mouth of the chimney interfering with the easy egress of the air causing moisture and carbon to be precipitated on the chimney top. To overcome such conditions cold air 115 is drawn to the duct into the flue 20 and tends to lower the temperature of the chimney above the points 21 and 22 and prevent the objectionable hovering of air above the chimney top.

In the application of the invention, the salient features thereof are subject to being employed in a room or rooms or a building of various room arrangements and in adapting the invention to different conditions 120

such changes in the location and the number of elements may be made as occasion requires without departing from the spirit of the invention. For example, one such construction as described may be situated in one room or a building and caused to ventilate that room alone or adjoining room or rooms not adjoining, but communicating with the flues by the air duct; or one or more ducts 5 may lead to various points in one room or to remote points in several rooms and communicate with the vent flues, these ducts may be so placed in a room in relation to the air inlet as to cause any desired ventilating, 10 or air conditioning effects such as ordinarily accrue from proper location of inlets and outlets.

I claim:

1. A ventilating system comprising an open fireplace partially surrounded by walls, 20 an inclosure situated in said fireplace, a heating element within said inclosure, air ducts leading from the upper portion of said open fireplace to said inclosure, a smoke flue communicating with said fireplace and adapted to carry off products of combustion, vent flues opening along with said smoke flue into a common chimney, said openings being so disposed in relation to each other 25 and to the smoke flue opening that the upward rise of products of combustion in said smoke flue will induce a similar upward rise in said vent flues, and ducts leading from remote points and communicating with 30 said vent flues.

2. A ventilating system comprising an open fireplace partially surrounded by walls, an inclosure situated in said fireplace, a heating element within said inclosure, air 40 ducts leading from the upper portion of said open fireplace to said inclosure, a smoke flue communicating with said fireplace and adapted to carry off products of combustion, vent flues opening along with 45 said smoke flue into a common chimney said openings so disposed in relation to each other and to the smoke flue opening whereby the upward rise of products of combustion in said smoke flue will induce a similar upward 50 rise in said vent flues, ducts leading from remote points and communicating with said vent flues, and a cold air duct leading from the atmosphere to one of 55 said flues and adapted to deliver cold air to said chimney to lower the temperature of the contents thereof before said contents are discharged.

3. In a ventilating system, a heating element in combination with a flue opening to a suitable chimney to carry out products of combustion, one or more vent flues opening into said chimney at various points so situated in relation to said smoke flue that an upward flow in said smoke flue will induce similar upward flow of air in said vent flue, 65 and ducts leading from remote points in said vent flue; whereby the natural tendency of the products of combustion to cause rapid rising to the said vent flue will promote removing the foul air from remote points. 70

4. In a ventilating system, a heating element in combination with a flue opening into a suitable chimney to carry out products of combustion, air ducts leading from remote points in the room to the said smoke flue and 75 adapted to conduct foul air from said remote points to said smoke flue, one or more vent flues opening into said chimney at a point so disposed in relation to the openings of said smoke flues that the upward flow of air 80 and products of combustion in said smoke flues will induce a similar upward flow of air in said vent flues, and ducts leading to said vent flues from remote points whereby the rising products of combustion will promote the removing of foul air from remote 85 points.

5. In a ventilating system, a heating element in combination with a flue opening into a suitable chimney to carry out products of 90 combustion, air ducts leading from remote points in the room to the said smoke flue and adapted to conduct foul air from said remote points to said smoke flue, one or more vent flues opening into said chimney at a 95 point so disposed in relation to the openings of said smoke flues that the upward flow of air and products of combustion in said smoke flues will induce a similar upward flow of air in said vent flues, ducts leading 100 to said vent flues from remote points whereby the rising products of combustion will promote the removing of foul air from remote points, and an air duct leading from the atmosphere to one of said flues and 105 adapted to deliver cold air to said chimney at a point situated above the opening of the other of said flues whereby an upward flow occasioned in said smoke flue will induce foul air to be drawn from remote points and 110 further induce cold atmospheric air to be drawn into the chimney to reduce the temperature of the contents thereof.

ELMER PEMBERTON.
